UNITED STATES PATENT OFFICE.

PASQUALE L. MOCCIA, OF NEW YORK, N. Y.

SWITCH-HEATER.

1,280,107.

Specification of Letters Patent. Patented Sept. 24, 1918.

Application filed March 15, 1918. Serial No. 222,672.

To all whom it may concern:

Be it known that I, PASQUALE L. MOCCIA, a citizen of the United States, residing at New York, in the county of New York and 5 State of New York, have invented new and useful Improvements in Switch-Heaters, of which the following is a specification.

This invention relates to improvements in heating devices and has particular reference 10 to a means for heating railway switches.

The primary object of the invention is the provision of a simple, inexpensive and effective device of the class described which will thoroughly heat the switch points to 15 prevent the formation of ice thereon.

Another object of the invention is the provision of a device of the character described which will thoroughly and quickly thaw out 20 a frozen switch which has been rendered inoperative due to the accumulation of ice or snow in the path of movement of the switch point.

A further object of the invention resides in the provision of a device of this character 25 which can be readily applied to the switch and supported from the ties and which will also include means whereby the degree of heat may be regulated at the will of the operator to meet varying conditions.

30 A still further object of the invention is to provide a device of this character which will include a retort or heating chamber adapted to receive a liquid fuel and convey the same to an underlying tray from which 35 the fuel is adapted to be ignited and to heat the retort so that the fuel will be vaporized to an appreciable extent and thereby permit heat of a high intensity to be produced with a minimum consumption of 40 fuel.

Figure 1 is a plan view of a portion of a track structure showing the application of the invention thereto.

Fig. 2 is a section taken on line 2—2 of 45 Fig. 1.

Fig. 3 is a transverse section taken substantially on the line 3—3 of Fig. 2.

Fig. 4 is a longitudinal section through the retort.

50 The invention comprises a suitable number of trays 5, which are adapted to be supported from the ties in positions beneath the switch points. Each of these trays is provided with an open top which is closed by 55 a removable cover plate 6, the same having perforations 7, therein for the outlet of the

heat against the superposed rails of the track structure as clearly indicated in Figs. 2 and 3. Each of these trays is supported from horizontal angle bars 8, which are 60 permanently suspended from side guard plates or shields 9—9. The said plates or shields are positioned against the inner surfaces of the ties and as shown, they are provided with flanges 10, which project over 65 the ties and which are adapted to be secured thereto by fastenings 11. In this manner, the trays are properly suspended from beneath the rails and the ties are preserved against damage by fire. The side 70 walls of said trays are provided with suitable air passages 12, in order that combustion of the gases will be properly promoted within said trays.

Extending lengthwise of the track structure are reservoirs 13 which are adapted to contain a liquid fuel, such as crude oil. These reservoirs are respectively connected with the adjacent trays and as illustrated, the reservoir at one side of said track structure 80 is provided with pipe sections 14 which extend in the direction of the adjacent trays 5 and the same have their terminal ends threaded or otherwise suitably connected at 15 with heating chambers or retorts 16. 85 One of these retorts is provided for each of the trays 5 and as illustrated in Fig. 2, it is supported from the end walls of said tray and positioned slightly above the bottom. On the bottom of each tray and beneath the 90 retort is placed a layer of pulverized asbestos 17. The retort is provided with a plurality of perforations 18 which open in the direction of the asbestos in order that fuel when administered to the retort will, 95 in turn, be distributed on to said asbestos. Located within each of said retorts is a heating core 19 which consists preferably of a single bar of metal. The pipe sections 14 which lead from the mentioned reservoirs 100 to the trays 5, are provided with controlling valves 20 whereby the flow of liquid fuel to the retorts can be satisfactorily regulated.

In practice, the devices are arranged beneath the switch points and fuel is permitted to enter the retorts and to initially drip on to the asbestos. The retorts then become properly heated and as fuel continues to be fed to said retorts, the same is thoroughly vaporized and transformed into 110 a highly gaseous matter. The heating core 19 which is provided for each of said re-

retorts serves to an appreciable extent to improve the vaporizing characteristics thereof. The said core has a diameter which is appreciably less than the internal diameter 5 of the retort in which it is fitted in order that a free circulation of fuel is established.

What I claim as new is:

1. A heating device of the character described comprising a plurality of guard 10 plates adapted to be suspended from spaced ties beneath the superposed rails, a tray supported from said plates and adapted to underlie the rails, a perforated cover removably fitted to said tray, and a burner under- 15 lying said cover and fitted to the tray.

2. A heating device of the character described comprising a tray having perforations therein, a burner located within the tray and including an overlying retort, the 20 said retort having perforations therein opening in the direction of the burner, and

means for feeding liquid fuel to said retort.

3. A heater of the character described comprising a reservoir, a valved pipe leading from said reservoir, a retort connected with said pipe and provided with perforations, and a heating core arranged in said 25 retort.

4. A heater comprising a tray provided 30 with air intake passages, the said tray having a perforated portion, a retort extending through-out the length of the tray and provided with downwardly opening perforations, a burner underlying the retort 35 and consisting of a substance onto which liquid fuel is adapted to be conveyed and burned, and a heating core located within said retort.

In testimony whereof I affix my signature. 40

PASQUALE L. MOCCIA.
